UNITED STATES PATENT OFFICE.

MELVIN L. SMITH AND BERNHARD SCHAD, OF LOCKPORT, NEW YORK,
ASSIGNORS TO SMITH'S SUSPENSION CARRIAGE WHEEL COMPANY,
OF SAME PLACE.

TIRE-HEATING FURNACE.

SPECIFICATION forming part of Letters Patent No. 314,202, dated March 17, 1885.

Application filed January 2, 1884. (No model.)

To all whom it may concern

Be it known that we, MELVIN L. SMITH and BERNHARD SCHAD, citizens of the United States, residing at Lockport, in the county of Niagara and State of New York, have invented certain new and useful Improvements in Ovens for Heating the Tires of Wagon-Wheels, of which the following is a specification, reference being had therein to the accompanying drawings.

This invention relates to ovens and furnaces for heating tires of wagon-wheels and other articles to which it is adaptable; and it consists in certain improvements in the construction of ovens for such purposes, as hereinafter described and claimed.

In the accompanying drawings, Figure 1 is a perspective view of an oven having our improvements. Fig. 2 represents a vertical section of the oven, taken from front to rear. Fig. 3 is a perspective view showing certain parts of the oven. Fig. 4 is a perspective view illustrating the openings in front with slide-covers. Fig. 5 is a detached view of 25 stove or fire-box.

A designates the main building or shell of the oven, the whole being usually constructed of brick or stone and iron.

B indicates the stove or fire-box, located at 30 the bottom of the oven and under the tracks on which the tires rest when being heated, the said fire-box being provided with a chimney or smoke-pipe, C, and a door, C', in the main casing.

D is a door for opening and closing a man-hole provided for access to the interior.

The front wall of the oven has an opening, which is closed by means of the fixed vertical strips F, extended upward, as shown, and 40 the movable slides E inserted between them. The vertical pieces F are made of two flat pieces of metal bolted together, with rollers or washers a placed at intervals between them, thus forming spaces along their edges and bearing-points for the slides E, which are readily moved up and down severally for the insertion of the tires, or any of them, into the oven, as shown at G in Fig. 1.

Within the oven, directly back of the front 50 openings, is fixed a frame to receive the tires G and support them in position, said frame consisting of the vertical rods I, secured to the oven at their upper ends, the horizontal

rods J, and the tracks or ways H, in which the tires rest. The said tracks extend rearward from the slots or openings, in which are placed the slides E, the rear ends of the tracks being supported by the rods I, attached thereto. The said tracks, as seen in Fig. 2, are inclined somewhat upward from the front, forming an inclined plane, so that when it is desired to take out a tire, the slide being raised, the tire, from its own gravity, moves forward through the opening.

The closed stove B extends along under the frame which supports the tires when being heated, the lower part of the frame, in which the tracks are formed, having openings through which the heat has free passage to the tires, which are all heated simultaneously and uniformly, a small quantity of fuel being required.

Either of a number of tires in the oven may be removed therefrom without disturbing any of the others, and without material loss of heat.

As seen at b in Fig. 2, the interior surface of the oven is made to conform somewhat to the shape of the tires for economy of heating-space.

We claim—

1. A heating-oven for tires of wheels, having in the front of its casing openings with slide-covers, in combination with a fixed frame and inclined tracks, directly in rear of such openings, for supporting the tires, substantially as shown and described.

2. In combination with a heating-oven, the vertical front pieces, F, and the slides E, in combination with a supporting-frame within the oven, having inclined tracks H, and a heating-stove under the frame, substantially as set forth.

3. In a heating-oven for tires, the strips F and slides E, in combination with a fixed frame, I J, and tracks H, and stove B, substantially as shown and described.

4. In combination with a heating-oven, the vertical parts F, provided with rollers a, and the intervening slides E, substantially as shown and described.

In testimony whereof we have affixed our signatures in presence of two witnesses.

MELVIN L. SMITH.

Witnesses: BERNHARD SCHAD.
